CLAIM

The ornamental design for a humidor, as shown and described.

DESCRIPTION

FIG. 1 is a perspective view of the first embodiment of the humidor of the present invention, having a textured surface and a flat cap;

FIG. 2 is a perspective view of the first embodiment of the humidor of the present invention with the cap exploded to reveal the design features therein;

FIG. 3 is a side elevational view of the first embodiment of the humidor of the present invention, all other side elevational views being identical;

FIG. 4 is a side elevational view of the first embodiment of the humidor of the present invention with the cap exploded;

FIG. 5 is a top plan view of the first embodiment of the humidor of the present invention with the cap in place, the top plan view of the second embodiment being identical;

FIG. 6 is a bottom plan view of the first embodiment of the humidor of the present invention, the bottom plan view of the second embodiment being identical;

FIG. 7 is a bottom plan view of the cap of the first embodiment of the humidor of the present invention, the bottom plan view of the cap of the second embodiment being identical;

FIG. 8 is the perspective view of the second embodiment of the humidor of the present invention, having a wood grain surface and a flat cap;

FIG. 9 is a perspective view of the second embodiment of the humidor of the present invention, with the cap exploded to reveal the design features therein;

FIG. 10 is a side elevational view of the second embodiment of the humidor of the present invention, all other side elevational views being identical; and,

FIG. 11 is a side elevational view of the second embodiment of the humidor of the present invention, with the cap exploded.
